UNITED STATES PATENT OFFICE

ERNEST E. HILL, OF CHICAGO, ILLINOIS, ASSIGNOR TO RITE-RITE MFG. CO., OF CHICAGO,
ILLINOIS, A CORPORATION OF ILLINOIS

CLIP FOR PENCILS

Application filed September 12, 1931. Serial No. 562,450.

This invention relates to a clip for permanent attachment to a pencil or pen body for engagement with a pocket flap in a familiar manner.

5 The object of the invention is to provide a clip of simple, economical and strong construction and a means for attaching it to the pencil body in such manner that it will present the required rigidity against movement 10 on the pencil body.

In the drawing:—

Figure 1 is a perspective view of a pencil provided with my improved clip.

15 Figure 2 is a transverse section through the pencil and base of the clip.

Figure 3 is a top plan view of the clip on an enlarged scale.

Figure 4 is a transverse section through the same on the line 4—4 of Figure 6.

20 Figure 5 is an enlarged side elevation of a drive screw used in applying the clip to the pencil.

Figure 6 is a side elevation of the clip on a scale like that of Figure 3.

25 Referring now to that embodiment of the invention illustrated in the drawing:—10 11 indicates a pencil body of any suitable construction, as for example a bakelite barrel for a mechanical pencil, although it will be understood that the invention is applicable to pencil bodies of any kind. 11 indicates the pencil as a whole and 12, 12 indicate two longitudinally spaced drive screws by which the clip is secured to the body.

30 35 The clip 11 comprises an elongated base 13 by means of which it is attached to the pencil body. The main part of the clip is bent away from the base to present a shoulder 14 beyond which the clip is tapered towards its end where it is preferably formed with a ball or other smooth termination 15 to facilitate its easy insertion into the pocket.

The clip is stamped from flat metal. The base 13 is flat transversely, as indicated at 13^a in Figure 2. At the lateral edges of said flat part the metal is bent at an obtuse angle to present ribs 13^b which extend the length of the base and act to stiffen it.

40 The main body of the clip beyond the base 50 is bent transversely into arcuate section, as

indicated at 11^a in Figure 4. This transversely curved section is preferably carried out throughout the length of the clip, thus greatly strengthening the clip against bending.

55 To attach the clip to the body or barrel, said barrel is provided with suitable longitudinally spaced apertures 16, 16 corresponding in spacing with similarly longitudinally spaced apertures 17 in the base 13. The base 60 is secured to the barrel by means of the drive screws 12, 12.

65 As pencil barrels of the kind are generally made hexagonal in cross section, the clip base is preferably made of such width that its flat part 13^a is equal in width to the width of the flat faces of the pencil. This permits a substantial area for base engagement by the clip on the pencil and also brings the strengthening ribs 13^b slightly beyond the width of the 70 pencil base to which the clip is attached, thus preventing said ribs from interfering with the flat seat of the clip base against the pencil body.

75 I have found that clips formed in the manner above described and attached to pencil bodies, as shown, are not only economical to manufacture in quantities, but are readily and easily attached to the pencil bodies and are very rigid and fixed in their final relation 80 to the pencil body.

I claim as my invention:—

85 In combination with a pencil body, a clip consisting of a base member and of a clip member, said base member being flat and being provided at its lateral edges with narrow flanges bent at an angle to the base, and the clip member being of transversely curved section substantially throughout its length with its lateral margins continuous with the flanges of said base, said base being provided with two longitudinally spaced apertures and drive screws engaged through said apertures and securing said base to said pencil body.

90 95 In testimony that I claim the foregoing as my invention, I affix my signature this 1st day of September, A. D. 1931.

100 ERNEST E. HILL.
